[57] **CLAIM**

The ornamental design for a lantern, as shown and described.

DESCRIPTION

FIG. 1 is a top plan view of a lantern of one embodiment of the invention;

FIG. 2 is a left side plan view of the lantern of FIG. 1;

FIG. 3 is a rear plan view of the lantern of the FIG. 1;

FIG. 4 is a right side plan view of the lantern of FIG. 1;

FIG. 5 is a front plan view of the lantern of FIG. 1;

FIG. 6 is a bottom plan view of the lantern of FIG. 1; and, FIG. 7 is a right plan view of the lantern of FIG. 1 with compartment open.

The broken lines in the figures are for environmental purposes only and form no part of the claimed design.
